VENETIAN BLIND STRUCTURE

Lewis I. Kahn, Jamaica, N. Y.

Application May 11, 1944, Serial No. 535,065

9 Claims. (CL. 160—170)

This invention relates to Venetian blinds and, more particularly to blinds which consist of a plurality of slats suspended by tapes, having means to raise and lower the slats and to tilt them at different angles to admit varying degrees of light.

In the ordinary type of blinds a plurality of cords extend down through the slats to the bottom rail so that the blinds may be raised and lowered. It is customary to have these cords extend through openings in the slats. With this construction it is impossible to remove the slats from the cords without totally dismantling the blind and this requires a factory job. Moreover, these cords are inclined to wear and fray where they are engaged by the pulley and locking means and to break or stick.

An object of this invention is to provide a blind in which the cords as such are eliminated and in which the individual slats are supported on the ladder or stirrup by detachable means. In the old construction it was impossible to remove the slats for cleaning purposes without dismantling the entire blind and one of the purposes of the present invention is to provide a structure where the slats may be individually removed and replaced without difficulty.

A further object is to provide a structure in which the slats which are readily removable are securely held in place and are centered on the ladders and stirrups so that they turn evenly when the slats are tilted and they do not stick or slide.

Other objects and advantages of the invention will become apparent from the description and the accompanying drawings, in which—

Figure 1 is an elevation partly in section of a blind embodying my invention;

Fig. 2 is a detailed view in section;

Fig. 3 is a sectional view taken on the line 3—3 showing tilting mechanism;

Fig. 4 is a sectional view taken on the line 4—4;

Fig. 5 is a detailed view showing the manner of positioning the individual slats;

Fig. 6 is a sectional view taken on the line 6—6 of Fig. 5;

Fig. 7 is a cross sectional view taken on the line 7—7 of Fig. 5;

Fig. 8 is a detailed view of one form of the slat supporting means;

Fig. 9 is a view of a tape embodying a modification of my invention;

Fig. 10 is a perspective view showing a slat 55

supporting member adapted to be used in the structure shown in Figure 9;

Fig. 11 is a modification of the form shown in Fig. 9;

Fig. 12 is a further modification of the slat supporting member.

Referring more particularly to the drawings, I provide a box member 15 in which is mounted a blind supporting mechanism which includes a rod member 16 and roller 17. Rod member 16 may be in any desired shape and preferably extends from adjacent one end of the blind to adjacent the other end. The rod member 16 is supported at one end by the bracket 18 and is pivotally mounted therein at 19. At the other end of the rod 16 pin 20 engages the sleeve 21 which has an arm 22 fastened to the top of the rod 16 by means of the screw 23. The sleeve 21 is mounted in the bracket 24 and has a spring 20 25 positioned between the flange 26 and the bracket 24. An arm 27 is affixed to the end of the sleeve 21. The arm 27 has two ends 28 and 29 to which are fastened the tapes or cords 30 and 31. A plurality of double tape members 35 and 36 are mounted on the rod 16 and depend therefrom to the bottom rail 37 where they are fastened in the conventional manner to either side thereof.

Mounted on the sleeve 21 and constituting an extension of the arm 22 is a pinion 38 engaging gear 39 mounted on the shaft 40. The shaft 40 also supports a spring 41 which is positioned by the flange 42 and bracket 24 to tension the turning thereof. It will be seen that by operating the tapes 30 and 31 the angle of the rod 16 will be changed and that this change will be transmitted by the tapes 35 and 36 to the bottom rail 37 and to each of the slats therein as will be more fully described hereafter.

As shown in Figures 1 to 8 inclusive, the conventional ladder member 50 is sewn or woven into the tape 35 and 36 to connect the two tapes. This may be secured in any desired way but in present practice these ladder members are woven into the tapes and alternate from side to side, particularly as shown in Figure 6 and indicated by the numerals 51 and 52. In ordinary commercial use the slats 55 are supported by the ladder members 50 and are free to slide thereon, being positioned by means of a cord extending between the alternate ladder members and extending through the center of the slats. Because of this cord it is impossible to remove the slats without dismantling the blind. In my im-

proved construction I provide a slat supporting member 56 shown in detail in Figure 8.

Member 56 may be made out of metal, plastic, or any similar material but is preferably semi-rigid. It is provided at either end with a pair of lugs 57 and 58 which are adapted to be bent about the ladder member 50 to firmly grip it and to position the tape 35 and 36 a uniform distance apart. Mounted on the member 56 is a stud 59 similar to that found in the conventional snap fastener. Slats 55 are provided with an opening 60 which may or may not be fitted with the female part of a snap fastener. In any event, the opening 60 is of such a size as to enable the stud 59 to be snapped therethrough and to hold the slat from lateral movement. The stud 59 may be mounted in a slot 61 to slide therein in order to allow for irregularities in the hole 60. It will be seen that by operating the cords 38 and 39 the angle of the ladder member or stirrup 50 and also of the slat carrying member 56 and the slat 55 may be changed. Since the slats are more or less rigidly positioned each slat will turn at the same angle and there will be no possibility of their sliding or sticking. Since the pinion 38 engages the gear 39, the action of the springs 25 and 41 is sufficient to create adequate friction to maintain the bar 16 at whatever position it is left.

The roller 17 is pivotally mounted at either end in the brackets 18 and 24 and adjacent one end thereof is mounted the tape 65 rolled thereon at 67. For each set of double tapes there is mounted on the roller 17 a continuous tape extending along the double tapes at 70 and 71 and rolled about the roller 17 at 72 and 73. The tape extends along the side of the tape 36 as indicated at 78 under the bottom rail and along the tape 35 as indicated at 71. The tape 70 and 71 is free to slide under the bottom rail so that when the slats are tilted the length of the blind will not be altered. Mounted on the bottom 15 of the box member 15 is a catch member 76 adapted to engage the tape 65 against the side 77 of the aperture through which the tape passes. It will be seen that as the tape 65 is pulled the bottom rail 37 and successive slats 55 will be raised toward the box. If the tape member is moved to the left the catch 76 will position it against the side 77 of the aperture and hold it in position. The tape member 65 is wound in the opposite direction from the tape 71 and 70 so that as the tape 65 is unwound tape 71 and 70 will be wound upon the roller 17. The bracket 18 is provided with a slot 80 so that the rod 16 may be removed therefrom and the bracket 24 is provided with a similar slot.

In the form shown in Figure 9, tape 90 is provided with a pair of tape members 91 and 92 attached thereto by means of stitching, an adhesive, or in any other conventional manner. These tapes are provided at predetermined intervals with eyes or eyelets 93. In this case the slot supporting member 95 is provided with hook members 96 adapted to engage the eyelets 93 and to support the slot supporting member 95 thereon. It will be appreciated that in Figure 9 only one of a double set of tapes is shown and the corresponding tape would be similarly constructed so that the member 95 would extend horizontally between the tapes. In Figure 11 the tapes 91 and 92 are provided with a U-shaped eye 97 adapted to engage the end 98 of the member 99. The member may be formed of wire bent upon itself to provide the stud 100 and the ends 98 which would be inserted through and supported by the members 97.

It will thus be seen that I have provided an attractive practical blind in which the slats may be readily removed for cleaning purposes and replaced without upsetting the hanging of the blind or without returning it to the factory for re-assembly. It will also be appreciated that many changes may be made in my structure without materially affecting the invention thereof thereby and that a number of variations thereof may be made, for instance, the ladders may all be centered and the tapes placed adjacent thereto, if desired.

I claim:

1. In a Venetian blind having a plurality of slats having openings therein and tapes supporting said slats said tapes being joined by cross members, of means for positioning said slats, said means comprising a member adapted to be fastened to one of said cross members and having a stud therein releasably engaging one of said openings in one of said slats.

2. A device for positioning apertured slats on the cross tapes of conventional Venetian blind ladders comprising an elongated member, lugs at each end of said member adapted to engage the associated cross tape and a stud on said member adapted to engage an aperture in the associated slat.

3. In combination with a Venetian blind having apertured slats and a pair of tapes provided with engaging means supporting said slats of means for supporting one of said slats comprising a member, a stud on said member engaging an aperture in said slat and lugs on the ends of said member adapted to engage the engaging means on said tapes.

4. A Venetian blind having a bottom rail and a plurality of slats and supporting tapes therefor, a pair of rods, one of said rods supporting said tapes, means for rotating said rod to a selected angular position, spring means for frictionally holding the position of said rod, a pair of tapes on the second of said rods extending along and inside of each pair of said supporting tapes to said bottom rail, and an additional tape wound on said second rod in an opposite direction to said pair of tapes for winding said pair of tapes on said second rod.

5. In a Venetian blind structure having supporting tapes, slats, a rotatable rod and a bottom rail, means for raising and lowering said blind, said means comprising a pair of tapes fastened to opposite sides of the bottom rail of said blind and extending on opposite sides of said slats inside of said supporting tapes to said rod, said tapes being wound in the same direction on said rod, an additional tape member wound in the opposite direction on said rod, and means for holding said additional tape member in selected positions.

6. In a Venetian blind structure having supporting tapes and apertured slats, a slat supporting member comprising an elongated body, a stud on said body adapted to engage an aperture in said slats, and means for fastening said member to said supporting tapes.

7. A Venetian blind structure having supporting tapes, a pair of tapes fastened to the inner sides of said supporting tapes, eye members on each of said pair of tapes, and a slat supporting body having means to engage said eye members.

8. In a Venetian blind structure having a plurality of slats, a bottom rail, and a pair of slat and rail supporting tapes, a pair of rod members one of said rod members supporting said sup-

porting tapes, means for tilting said rod member, the other of said rod members having wound thereon a plurality of pairs of tape members, said last-mentioned tape members extending along and inside of said supporting tapes to said bottom rail on each side of said slats, and means for rotating said rod member to wind said pair of tapes to raise said blind.

9. In a Venetian blind structure a slat supporting member comprising a wire bent upon itself to form a stud at approximately the center thereof adapted to engage an aperture in said slat, said wire being bent at each end thereof to engage the supporting tapes of said blind structure.

LEWIS I. KAHN.
